UNITED STATES PATENT OFFICE.

SAMUEL W. POTTS, OF BROOKLYN, NEW YORK, ASSIGNOR TO ENGLANDER SPRING BED COMPANY, OF BROOKLYN, NEW YORK, A CORPORATION OF NEW YORK.

CONVERTIBLE DIVAN OR COUCH-BED.

1,061,496.

Specification of Letters Patent.

Patented May 13, 1913.

Application filed October 28, 1912. Serial No. 728,023.

To all whom it may concern:

Be it known that I, SAMUEL W. POTTS, a citizen of the United States, residing at Brooklyn, in the county of Kings and State 5 of New York, have invented certain new and useful Improvements in Convertible Divans or Couch-Beds, of which the following is a specification.

This invention relates to convertible divans or couch beds, more particularly to that class known as divanettes, in which the structure when in the form of a divan is usually about four feet long, whereby it does not take up very much space lengthwise thereof in a room, and which divan is formed of three sections each about two feet wide, so that when opened up the structure will be converted into a full length bed, the object of the present improvement being to 10 provide a simple and comparatively inexpensive structure to make, and one which is easily operated, and comprising a stationary section and a pair of swinging sections, which swinging sections are shifted in opposite directions to form either a divan or a double bed on the manipulation of either of said swinging sections.

In the drawings accompanying and forming part of this specification Figure 1 is an 15 end view of this improved convertible divanette; Fig. 2 is an end view showing the same partly opened; and Fig. 3 is an end view showing the same opened to form a double bed.

Similar characters of reference indicate 20 corresponding parts throughout the figures of the drawings.

In the preferred form thereof this improved divanette comprises a stationary 25 middle section 2 and a pair of swinging sections 3 and 4 hinged thereto. The stationary section may comprise a pair of end frames 5, each consisting of a cross-bar or member 6 and suitable braced legs 7, which 30 may be provided with the usual form of casters, if desired. Stretched between the cross or end bars 6 is some suitable form of spring 8. Hinged to one, as for instance the

rear side, is the back or back section 4, which comprises a pair of end bars 10 suitably 50 connected by a lengthwise extending bar at their outer ends. The end bars are pivotally connected to the end frames of the stationary section 2, and as shown are provided with a pair of depending portions or members 11 forming levers for connection with the front swinging section in the manner hereinafter described. The end bars also carry a suitable spring. The front swinging section 3 likewise comprises a pair of end 60 bars 12, for supporting a suitable spring, pivotally connected to the front edge or side of the stationary frame or section 2, and these end members are suitably connected at their outer ends by a lengthwise 65 extending bar. Pivotally connected to the depending portions of the back at each end of the structure is a link 13 shown as of bent formation, so as not to project above the seat of the structure when in the form 70 of a divan. Each link is provided with a slot 14 for the reception of a headed pin or stud carried by the front swinging section, and secured, or formed as a part of this link, at its forward end is a suitable leg or 75 support 15 for the front swinging section this leg being connected with the link itself by a suitable brace 17. Pivotally secured to the back end bars, one at each end, is a leg or support which will fold into position 80 to support the back when it is lowered, and will extend along the back ends when it is raised.

Any suitable form of stuffed mattress may be used, which, when the structure is 85 in the form of a divan, may be on top of the swinging section 3 and when it is desired to convert the structure into a double bed this may be thrown up against the back to permit the structure to be opened, and 90 then thrown over upon the stationary section and the front swinging section. The back of course, also will carry a stuffed mattress.

To transform the structure into a double 95 bed the user simply grasps the front swing-

ing section and swings it over into the position shown in Fig. 2 and then into the position shown in Fig. 3. This operation of the front swinging section simultaneously 5 operates the back section and lowers it into the position shown in Figs. 2 and 3. By reversing this operation the structure is again converted into a divan.

The springs of the stationary and swing- 10 ing sections may, of course, each be separate, one from another, but in practice, in view of the construction, one continuous fabric or spring may be used for the middle and front swinging and back sections, this 15 fabric being herein designated as 8.

I claim as my invention:—

1. A divanette comprising a stationary middle section, a spring fabric secured thereto and fixed against movement, where- 20 by it is always normally maintained permanently level, a pair of swinging sections, each of which also has a similar spring, hinged to said stationary middle section, said swinging sections being movable in op- 25 posite directions whereby when fully opened they form with the stationary middle section a full length bed, and means connect- 30 ing said swinging sections so that on the shifting of one of them the other will be shifted, the spring of one of said swinging sections adapted to rest flatwise over the spring of the stationary middle section and form therewith the seat when the structure 35 is in the form of a divan, and the other swinging section adapted to extend perpen- dicularly to form the back.

2. A divanette comprising a stationary middle section and a pair of swinging sections hinged thereto at opposite sides there- 40 of, one forming the back and the other the seat when the structure is in the form of a divan, and movable in opposite directions to form a full length bed, and means connect- 45 ing the two swinging sections together whereby on swinging one of them the other will be also swung, said means having a sliding connection with the front swinging section.

3. A divanette comprising a stationary middle section and a pair of swinging sections hinged thereto at opposite sides there- 50 of, one forming the back and the other the seat when the structure is in the form of a divan, and shiftable in opposite directions to form a full length bed, and means connect- 55 ing the two swinging sections together whereby on swinging one of them the other will be also swung, said means having a sliding connection with the front swinging 60 section and also having a depending leg portion for supporting the front swinging section.

4. A divanette comprising a stationary section, a back hinged thereto at one side

and having a depending lever portion, a 65 front swinging section hinged at the oppo- site side of said stationary section, a link connecting the depending portion of the back with said front swinging section, said swinging section and link having one a stud 70 and the other a slot, and means carried by the structure for supporting the front swing- 75 ing section when the structure is converted into a full length bed.

5. A divanette comprising a stationary 75 section and back hinged thereto at one side and having a depending lever portion, a front swinging section hinged at the oppo- 80 site side of said stationary section, a link connecting the depending portion of the back with said front swinging section, said swinging section and link having one a stud and the other a slot, and means for support- 85 ing the front swinging section when the structure is converted into a full length bed, 90 said means being carried by said link.

6. A divanette comprising a middle sec- 90 tion, a back hinged thereto and having a de- pending portion and a front section hinged to said middle section, said front 95 and back being movable in opposite direc- tions to convert the structure into a full length bed, and a link connecting the back with the front section, said link having, when the structure is in the form of a divan, 95 a portion substantially parallel with the end of the structure and an inclined portion.

7. A divanette comprising a middle sec- 100 tion, a back hinged thereto and having a de- pending portion and a front section hinged 105 to said middle section, said front and back being movable in opposite directions to convert the structure into a full length bed, and a link connecting the back with the front section, said link having, when the struc- 110 ture is in the form of a divan, a portion substan- tially parallel with the end of the structure and an inclined portion, and said back having a depending portion connected with said link.

8. A divanette comprising a middle sec- 115 tion, a back hinged thereto and having a de- pending portion and a front section hinged to said middle section, said front and back being movable in opposite direc- 120 tions to convert the structure into a full length bed, and a link connecting the back with the front section, said link having, when the structure is in the form of a divan, a portion substan- tially parallel with the end of the structure and an inclined portion, and said link having at its forward end a depending portion adapted to form a support for the front section.

9. A divanette comprising a middle sec- 125 tion, a back hinged thereto and having a de- pending portion and a front section hinged to said middle section, said front and back

being movable in opposite directions to convert the structure into a full length bed, and a link connecting the back with the front section, said link having, when the structure is in the form of a divan, a portion substantially parallel with the end of the structure and an inclined portion, said link hav-

ing a pin and slot connection with the front section.
